UNITED STATES PATENT OFFICE.

WILLIAM HALE DRIGGS, OF WASHINGTON, DISTRICT OF COLUMBIA,
ASSIGNOR TO THE DRIGGS-SEABURY ORDNANCE CORPORATION,
OF SHARON, PENNSYLVANIA, A CORPORATION OF PENNSYLVANIA.

SHELL-FUSE.

No. 818,943.

Specification of Letters Patent.

Patented April 21, 1906.

Application filed March 11, 1905. Serial No. 249,638.

To all whom it may concern:

Be it known that I, WILLIAM HALE DRIGGS, a citizen of the United States, residing at Washington, in the District of Columbia, have invented certain new and useful Improvements in Shell-Fuses; and I do hereby declare the following to be a full, clear, and exact description of the invention, such as will enable others skilled in the art to which it appertains to make and use the same.

My present invention relates to improvements in percussion-fuses for shells, and more especially to that class of fuses in which the firing-plunger is held in the safety position by means of resilient arms, which arms are released by centrifugal action due to the spinning up of the shell when fired from the gun.

This invention is intended more especially as an improvement upon the fuse shown and described in my Patent No. 419,143, granted January 7, 1890.

My invention will be understood by reference to the accompanying drawings, in which the same parts are indicated by the same letters throughout the several views.

Figure 1 shows a section through the nose of a small shell fitted with my improved fuse. Fig. 2 shows a similar section through a modified form of fuse, but taken at right angles to the section shown in Fig. 1. Fig. 3 shows a similar section to that indicated in Fig. 2, but with slightly-modified form of fuse. Fig. 4 shows a section similar to that indicated in Fig. 1, except that a base-fuse is shown, whereas in Figs. 1 to 3 point-fuses are shown. The invention is intended to be fully applicable to either point-fuses or base-fuses. Fig. 5 shows in perspective, on an enlarged scale, the plunger indicated in Figs. 1 to 4. Fig. 6 shows a front view of the plunger indicated in Fig. 1. Fig. 7 shows a side elevation of the centrifugal spring - arms which normally hold the plunger in the safety position, said arms being detached from the plunger and being shown on an enlarged scale. Fig. 8 is a view of the device shown in Fig. 7 as seen from the right of said figure; and Fig. 9 shows the spring-arms developed, on a reduced scale.

Referring first to Figs. 1 and 5 to 8, A represents the body of the shell, which is screw-threaded, as at *a*, to receive the screw-threads *b* of the fuse-stock *B*. This fuse-stock is

preferably provided with an ogival head *B'*, which may be notched, as at *b'*, (see Figs. 2 and 3 and shown in dotted lines in Fig. 1,) for convenience in screwing the fuse-stock into the shell. The fuse-stock is also screw-threaded, as at *b*², to receive the cap *C*. This cap is perforated, as at *c*, and is provided with a small vent-sealing cap or plug *c'*. Mounted in the fuse-stock is a plunger *D*, which is perforated axially, as at *d*, and this perforated portion is filled with meal-powder *H* in its rear end and with friction composition cemented into the front end about the serrated pin *F*, which projects somewhat beyond the face of the plunger, as shown in Fig. 1. The powder is kept from falling out of the perforation *d* by means of the cap *h*. The base of the plunger is preferably provided with lugs *d'*, (shown most clearly in Fig. 5,) which have overhanging lips *d'*² to embrace the central or heel portion *e'* of the spring-piece *E*. These lugs *d'* also fit in a notch in the fuse-cap *C*, so that the plunger shall be held against turning within the fuse-stock. The spring-piece *E* (shown in development in Fig. 9) is provided with a central perforation *e* to register with perforation *d* in the plunger to permit the passage therethrough of the flame from the primer and is also provided with two resilient arms *e*², carrying curved weights *e*³, which are recessed, as at *e*⁰. This spring-piece is slid into engagement with the lugs *d'*, and the resilient arms *e*² are then bent over into the slots *d*² in the plunger, so that they embrace the plunger, as indicated in Figs. 1 and 4. The head of the fuse-stock is provided with an inwardly-projecting cylindrical lug *b*³, surrounded with an annular groove, which lug forms the anvil.

The operation of the device is as follows: Suppose the parts to be in the position shown in Fig. 1 and the gun to be fired. The rifling will spin up the shell, which will cause the spring-arms *e*² to spring out, causing the weights *e*³ to clear the cylindrical lug *b*³ and causing the fuse to assume the firing position. If now the shell is suddenly arrested, as from striking the target, the plunger will fly forward, causing serrated pin *F* to strike the lug or anvil *b*³, igniting the friction composition, and with it the powder *H*, and thus exploding the shell.

In practice the plunger would probably

creep forward slightly, causing the weights e^3 to project into the annular recess surrounding the anvil, and thus holding the plunger in the firing position should the decreased rotary velocity of the shell be insufficient to keep the resilient arms e^2 extended, due to the action of centrifugal force. Thus when firing at long ranges, when the rotary motion of the shell will be comparatively slight, the fuse will still be operative.

In the form of device shown in Fig. 2, instead of the friction-primer, (shown in Fig. 1,) an ordinary percussion-cap I is shown mounted on a nipple d^4 on the plunger D, which cap strikes a firing-point b^5 on the anvil b^4 . The operation of the device is precisely the same as that referred to in Fig. 1.

In the form of device shown in Fig. 3, the magazine-primer K is screwed into the interior of the head of the fuse-stock and carries a perforated nipple k , on which is mounted the percussion-cap L. This percussion-cap is struck by a nipple d^6 on the plunger D. The operation of the device is precisely the same as has already been described with reference to Fig. 1, except that the flame from the magazine-primer is blown backward to the perforation d in the plunger.

The fuse shown in Fig. 4 embodies the same general principles as have already been described with reference to Figs. 2 and 3; but this figure shows a base-fuse in which the fuse-stock B² is screwed into the base of the shell and is closed by the cap M, having perforations m^0 . This cap is provided with an annular pocket m and a firing-point m' , above which point and in which pocket is mounted the percussion-cap N. This cap is struck by the firing-point d^6 on the plunger D. The operation of the fuse is precisely the same as that already described with reference to Figs. 1 and 2.

It will be noted that in all forms of the device the spring-piece E is carried by and moves with the plunger, and thus adds materially to the striking force exerted by the plunger when the motion of the shell is suddenly arrested. Furthermore, it will be seen that the weights e^3 , carried by the resilient arms e^2 , form a positive obstruction between the face of the plunger and the face of the anvil or of the part carrying the ignition device, which obstruction positively prevents any possible premature explosion of the primer until these weights are swung outward against the action of the spring-arms e^2 . There being two of these arms, there are thus two positive and effectual safeguards provided against any possible premature explosion of the shell due to the improper action of the fuse.

It will be seen that in each of the modifications hereinafter described there is an abutment integral with or rigidly attached to the fuse-stock, with a recess exterior to said abutment, and that the weights e^3 positively engage be-

tween abutment and the front face of the plunger when the parts are in the safety position, but register with the recess when the parts are in the firing position. This recess is shown as annular; but any suitable pockets for the weights e^3 at the sides of the abutment will serve the same purpose.

While I have shown various modifications of the same general idea, it will be obvious that various other modifications might be made which could be used without departing from the spirit of my invention.

Having thus described my invention, what I claim, and desire to secure by Letters Patent of the United States, is—

1. In a shell-fuse, the combination of a fuse-stock, a plunger normally held against rotation therein, means operated by the sudden forward motion of the plunger in the fuse-stock for firing said fuse, and a spring-piece having resilient weighted arms secured to said plunger and normally obstructing the forward motion of the plunger in the fuse-stock but swinging outward under the action of centrifugal force when the shell is spun up and then permitting said plunger to plunge forward when the motion of the shell is suddenly arrested, substantially as described.

2. In a shell-fuse, the combination of a fuse-stock, a plunger normally held against rotation therein, means operated by the sudden forward motion of the plunger in the fuse-stock for firing said fuse, and a spring-piece provided with two oppositely-disposed resilient weighted arms secured to said plunger and normally obstructing the forward motion of the plunger in the fuse-stock, but swinging outward under the action of centrifugal force when the shell is spun up, and then permitting said plunger to plunge forward when the motion of the shell is suddenly arrested, substantially as described.

3. In a shell-fuse, the combination with a fuse-stock, and cap, a plunger mounted in said fuse-stock, and provided with lugs engaging in a notch in said cap to normally prevent the plunger from rotating in said stock, and a spring-piece provided with two oppositely-disposed resilient weighted arms secured to said plunger and normally obstructing the forward motion of the plunger in the fuse-stock, but swinging outward under the action of centrifugal force when the shell is spun up and then permitting said plunger to plunge forward when the motion of the shell is suddenly arrested, substantially as described.

4. In a shell-fuse, the combination of a fuse-stock provided with an abutment having a recess at either side thereof, a plunger normally held against rotation in said stock, means operated by the sudden forward motion of the plunger for firing said fuse, and resilient weighted arms carried by said plunger and normally obstructing the forward

motion of said plunger but swinging outward under the action of centrifugal force when the shell is spun up and then registering with said recesses thereby removing said obstruction, substantially as described.

5. In a shell-fuse, the combination of a fuse-stock, provided with an abutment having a recess at either side thereof, a plunger normally held against rotation in said stock, means operated by the sudden forward motion of the plunger for firing said fuse, and a spring-piece provided with two oppositely-disposed resilient weighted arms carried by said plunger and normally obstructing the forward motion of said plunger but swinging outward under the action of centrifugal force when the shell is spun up and then registering with said recesses thereby removing said obstruction, substantially as described.

10. In a shell-fuse, the combination with a fuse-stock, provided with an abutment and an annular recess around same, a cap for said stock provided with a notch, a plunger mounted in said fuse-stock, and provided

15 with lugs engaging in said notch to normally prevent the plunger from rotating in said stock, and a spring-piece provided with two oppositely-disposed resilient weighted arms carried by said plunger and normally obstructing the forward motion of said plunger but swinging outward under the action of centrifugal force when the shell is spun up and then registering with said recesses, thereby removing said obstruction, substantially as described.

20. In a shell-fuse, the combination with a fuse-stock, provided with an abutment having a recess at either side thereof, a plunger normally held against rotation in said stock, means operated by the sudden forward motion of the plunger for firing said fuse, and a spring-piece provided with two oppositely-disposed resilient weighted arms carried by

25 said plunger and projecting in front thereof and normally obstructing the forward motion of said plunger but swinging outward under the action of centrifugal force when the shell is spun up and then registering with said recesses thereby removing said obstruction, substantially as described.

30. In a shell-fuse, the combination of a fuse-stock, a plunger normally held against rotation therein, means operated by the sudden forward motion of the plunger in the fuse-stock for firing said fuse, and a spring-piece secured to the base of said plunger provided with two forwardly-projecting oppositely-disposed resilient weighted arms carried by said plunger projecting to the front

35 of said plunger and normally obstructing the forward motion of the plunger in the fuse-stock, but swinging outward under the action of centrifugal force when the shell is spun up, and then permitting said plunger to plunge forward when the motion of the shell is suddenly arrested, substantially as described.

8. In a shell-fuse, the combination with a fuse-stock, and cap, a plunger mounted in said fuse-stock, and provided with lugs engaging in a notch in said cap to normally prevent the plunger from rotating in said stock, and a spring-piece secured between said lugs and provided with two oppositely-disposed resilient weighted arms carried by said plunger projecting to the front of said plunger and normally obstructing the forward motion of the plunger in the fuse-stock, but swinging outward under the action of centrifugal force when the shell is spun up and then permitting said plunger to plunge forward when the motion of the shell is suddenly arrested, substantially as described.

trifugal force when the shell is spun up and 65 then permitting said plunger to plunge forward when the motion of the shell is suddenly arrested, substantially as described.

9. In a shell-fuse, the combination of a fuse-stock provided with an abutment having a recess at either side thereof, a plunger held against rotation in said stock, means operated by the sudden forward motion of the plunger for firing said fuse, and resilient weighted arms carried by said plunger and 70 projecting in front thereof and normally obstructing the forward motion of said plunger but swinging outward under the action of centrifugal force when the shell is spun up and then registering with said recesses thereby removing said obstruction, substantially as described.

10. In a shell-fuse, the combination of a fuse-stock, provided with an abutment having a recess at either side thereof, a plunger 85 normally held against rotation in said stock, means operated by the sudden forward motion of the plunger for firing said fuse, and a spring-piece provided with two oppositely-disposed resilient weighted arms carried by 90 said plunger and projecting in front thereof and normally obstructing the forward motion of said plunger but swinging outward under the action of centrifugal force when the shell is spun up and then registering with 95 said recesses thereby removing said obstruction, substantially as described.

11. In a shell-fuse, the combination with a fuse-stock, provided with an abutment and an annular recess around same, a cap for said 100 stock provided with a notch, a plunger mounted in said fuse-stock, and provided with lugs engaging in said notch to normally prevent the plunger from rotating in said stock, and a spring-piece secured between 105 said lugs and provided with two oppositely-disposed resilient weighted arms carried by said plunger and projecting in front of and normally obstructing the forward motion of said plunger but swinging outward under the 110 action of centrifugal force when the shell is spun up and then registering with said recesses, thereby removing said obstruction, substantially as described.

12. In a shell-fuse, the combination of a 115 fuse-stock, a plunger normally held against rotation therein, a friction-primer ignited by the sudden forward motion of the plunger in the fuse-stock, and resilient weighted arms carried by said plunger and normally obstructing the forward motion of the plunger in the fuse-stock but swinging outward under the action of centrifugal force when the shell is spun up and then permitting said plunger to plunge forward when the motion of the 125 shell is suddenly arrested, substantially as described.

13. In a shell-fuse, the combination of a

fuse-stock, a plunger normally held against rotation therein, a friction-primer ignited by the sudden forward motion of the plunger in the fuse-stock, and a spring-piece provided with two oppositely-disposed resilient weighted arms carried by said plunger and normally obstructing the forward motion of the plunger in the fuse-stock, but swinging outward under the action of centrifugal force when the shell is spun up, and then permitting said plunger to plunge forward when the motion of the shell is suddenly arrested, substantially as described.

14. In a shell-fuse, the combination with a fuse-stock, and cap, a plunger mounted in said fuse-stock, and provided with lugs engaging in a notch in said cap to normally prevent the plunger from rotating in said stock, a friction-primer ignited by the sudden forward motion of the plunger in the fuse-stock, and a spring-piece provided with two oppositely-disposed resilient weighted arms carried by said plunger and normally obstructing the forward motion of the plunger in the fuse-stock, but swinging outward under the action of centrifugal force when the shell is spun up and then permitting said plunger to plunge forward when the motion of the shell is suddenly arrested, substantially as described.

15. In a shell-fuse, the combination of a fuse-stock provided with an abutment having a recess at either side thereof, a plunger normally held against rotation in said stock, a friction-primer ignited by the sudden forward motion of the plunger, and resilient weighted arms carried by said plunger and normally obstructing the forward motion of said plunger but swinging outward under the action of centrifugal force when the shell is spun up and then registering with said re-

cesses thereby removing said obstruction, substantially as described.

16. In a shell-fuse, the combination of a fuse-stock, provided with an abutment having a recess at either side thereof, a plunger normally held against rotation in said stock, a friction-primer ignited by the sudden forward motion of the plunger, and a spring-piece provided with two oppositely-disposed resilient weighted arms carried by said plunger and normally obstructing the forward motion of said plunger but swinging outward under the action of centrifugal force when the shell is spun up and then registering with said recesses thereby removing said obstruction, substantially as described.

17. In a shell-fuse, the combination with a fuse-stock, provided with an abutment and an annular recess around same, a cap for said stock provided with a notch, a plunger mounted in said fuse-stock, and provided with lugs engaging in said notch to normally prevent the plunger from rotating in said stock, a friction-primer ignited by the sudden forward motion of the plunger in the fuse-stock, and a spring-piece provided with two oppositely-disposed resilient weighted arms carried by said plunger and normally obstructing the forward motion of said plunger but swinging outward under the action of centrifugal force when the shell is spun up and then registering with said recesses and removing said obstruction, substantially as described.

In testimony whereof I affix my signature in presence of two witnesses.

WILLIAM HALE DRIGGS.
